(57) **CLAIM**

The ornamental design for an egg tray as shown and described.

DESCRIPTION

FIG. 1 is a top, front perspective view of an ornamental design for an egg tray showing our new design, wherein the egg tray is in an open position;

FIG. 2 is a bottom, front perspective view of thereof;

FIG. 3 is a front elevational view thereof;

FIG. 4 is a rear elevational view thereof;

FIG. 5 is a right elevational view thereof, the left elevational view being a mirror image thereof;

FIG. 6 is a top plan view thereof;

FIG. 7 is a bottom plan view thereof; and,

FIG. 8 is a top, front perspective view of the ornamental design for the egg tray shown in FIG. 1, wherein the egg tray is in a closed position.

The broken lines in the drawings illustrate portions of the egg tray that form no part of the claimed design.

1 Claim, 7 Drawing Sheets
